UNITED STATES PATENT OFFICE.

JAMES KEISTER, OF STEUBENVILLE, OHIO.

SINGLE-VALVE FOUR-CYCLE EXPLOSIVE-ENGINE.

1,144,208.

Specification of Letters Patent. Patented June 22, 1915.

Application filed January 30, 1914. Serial No. 815,427.

To all whom it may concern:

Be it known that I, JAMES KEISTER, a citizen of the United States, and a resident of Steubenville, in the county of Jefferson and State of Ohio, have invented a new and Improved Single-Valve Four-Cycle Explosive-Engine, of which the following is a full, clear, and exact description.

This invention relates to four-cycle engines of the single valve type in which the valve is in the form of a sleeve or tube having separate inlet and exhaust ports adapted to register respectively with the inlet and exhaust ports of the cylinder during the suction and exhaust strokes of the piston, said valve having one stroke back and forth with each cycle of the engine.

The present invention relates to improvements to engines of the type referred to, and more especially to the valve operating mechanism shown in my prior applications for Letters Patent Serial Number 770,347, of May 28, 1913, and Serial Number 802,917, of November 25, 1913.

In my prior valve operating mechanisms a lever mounted in the crank case is linked to the valve of the engine and the lever carries a roller which rides on an operating cam in engagement with which the roller is maintained by a spring acting in conjunction with the cam to reciprocate the valve. This construction is effective for certain engine speeds but for very high speeds it is not as effective as desired because of the momentum of the moving parts being too great to be opposed by the spring, and to overcome this by tightening the spring results in complications due to the high pressure and friction on the journals of the roller.

The general objects of the present invention are to provide a simple and effective valve operating mechanism especially adapted for high speed engines, although it is suitable for engines operating at a low speed, such valve mechanism embodying a pair of synchronously rotating complementary cams engaging opposite sides of the roller on the lever, which roller is of substantial dimensions, while the radii of the cam are reduced to a minimum for the purpose of preventing an excessively high peripheral speed thereof, which, together with the large roller, is conducive to long life, efficient operation and noiselessness.

With such objects in view, and others which will appear as the description pro-

ceeds, the invention comprises various novel features of construction and arrangement of parts such as will be set forth with particularity in the following description and claims appended hereto.

In the accompanying drawings, which illustrate one embodiment of the invention, and wherein similar characters of reference indicate corresponding parts in both the views, Figure 1 is a longitudinal section of an engine of the type referred to and equipped with the improved valve operating mechanism; and Fig. 2 is a diagrammatic view of the cams and roller.

Referring to the drawing, A designates a cylinder of any approved construction having an inlet port 1 and an exhaust port 2 preferably at opposite sides, and sliding in the cylinder is a single cylindrical or tubular valve B that is carefully finished as the piston C reciprocates therein, there being an inlet port 1^a in the valve and an exhaust port 2^a, these ports being so arranged that on the down or out stroke of the valve the port 2^a first registers with the port 2 so as to allow the fired gases to exhaust during the exhaust stroke, while the port 1^a registers with the port 1 during the suction stroke of the piston, and on the return stroke of the valve the inlet ports first close and then the exhaust ports quickly close, so that on the in or up stroke of the piston C the charge will be compressed, it being understood that this quick closing movement of the exhaust ports occurs while the piston C is moving very slowly from its dead center, and hence only a negligible quantity of fuel mixture can escape out of the exhaust ports during this passage of the valve port 2^a across the cylinder port 2.

The valve B extends into the crank case D and is connected by the link 3 with a lever 4 that is fulcrumed at one end 5 to one side of the crank case and extends across the piston rod 6 to the opposite side, where the free end of the lever has journaled thereon a large roller 7. Mounted on the crank case are cam shafts 8 and 8' which are suitably geared to the crank shaft 9 in such a manner that the cam shafts will rotate synchronously in the same direction and at the same speed. On these shafts are complementary cams 10 and 10^a which engage the roller respectively at points above and below the axis thereof. The term "complementary" as applied to the cams

has reference to the contour or peripheral shape thereof, and the cams are so shaped that both will always be in contact with the roller and cause the latter to move up and down in a curvilinear path about the lever 4 as a center, and consequently the lever will oscillate and reciprocate the valve B. The cams may be divided into four quarters a, b, c and d for the upper cam, 5 as shown in Fig. 2, and a', b', c' and d' for the lower cam, the section a of the upper cam corresponding to the section a' of the lower cam, and so on; and furthermore these quarter sections correspond respectively to the exhaust, suction, compression and expansion strokes in the cycle of the engine. Since the cams are complementary the sum of the two radii thereof that are effective at any time in engaging with the 10 lever roller 7, is equal to the sum of the radii engaging the roller at all points in the revolution of the cam, so that there will be no loose play, and one cam is always active in moving the roller up or down, 15 while the other cam is receding. Or, in other words, one cam is an actuator at one instant and the other cam is the actuator at another instant, and the only time the cams are not moving the roller up and down is 20 when the valve is idle, as, for instance, when its ports are registering with the corresponding ports of the cylinder. Considering the movement of the valve with respect to the cam 10, Fig. 2, the roller is 25 engaging the portion of the cam of smallest radius, and consequently the valve will be in its uppermost or closed position. This is the position of the valve at the beginning 30 of the explosion stroke of the piston, and during the working stroke of the piston the portion 11 of the cam rides over the roller and moves the lever, and hence the valve, 35 downwardly, so that the exhaust port of the valve will register with the exhaust port 40 of the cylinder when the portion 12 of the cam reaches the roller. The spent gases are now forced out during the major part of the exhaust stroke and toward the end of this stroke the eccentric part 13 of the cam 45 engages the roller 7 and moves the lever and valve still farther downwardly, whereby the exhaust ports close and the inlet port 14 of the valve registers with the inlet port 1 of the cylinder, and now the part 14 of 50 the cam holds the valve stationary during a considerable part of the suction stroke, when finally the decidedly eccentric part 15 of the cam rides over the roller and allows the lever to be moved upwardly by 55 the lower cam very rapidly, so that the inlet port will close and the exhaust port of the valve quickly pass the exhaust port of the cylinder. The piston now compresses 60 the charge which is duly fired and the cycle 65 of operation repeated.

It is obvious with the cam construction shown that the engine can have a very high speed, and yet the valve will always be positively operated without any lost motion, and at the same time wear and friction are 70 reduced to a minimum.

From the foregoing description taken in connection with the accompanying drawings, the advantages of the construction and method of operation will be readily understood by those skilled in the art to which the invention appertains, and while I have described the apparatus which I now consider to be the best embodiment thereof, I desire to have it understood that the apparatus shown is merely illustrative and that such changes may be made when desired as are within the scope of the appended claims.

Having thus described my invention, I claim as new and desire to secure by Letters Patent:

1. An explosive engine comprising a cylinder having inlet and exhaust ports therein, a tubular valve reciprocating in the cylinder, inlet and exhaust ports arranged in the valve 90 to register respectively with the corresponding cylinder ports during suction and exhaust strokes of the engine, a piston reciprocating in the valve, and a valve operating mechanism for moving the valve two steps 95 in one direction to first open the exhaust port and then open the inlet port while closing the exhaust port, and one step in the opposite direction to close both ports, said mechanism consisting of a pair of three step 100 complementary cams synchronously driven, a lever linked to the valve and a roller thereon engaging the said pair of complementary cams, each cam having an eccentric portion for reciprocating the valve in one continuous 105 stroke to close both ports, a concentric portion for holding the valve to remain closed during the major parts of the compression and expansion strokes of the piston, an eccentric portion for moving the valve to open 110 the exhaust port, a concentric portion for holding the valve in open-exhaust-port position, an eccentric portion for moving the valve still farther to close the exhaust port and open the inlet port and a concentric 115 portion for holding the valve in inlet-port-open position, the sum of the effective radii of the cams at every instant being constant.

2. A four cycle explosive engine including a single suction and exhaust valve having an 120 intermittent stroke in one direction to successively open an exhaust and a suction port and a continuous stroke in the other direction for intercepting communication with exhaust and intake ports on its return movement, an element connected with the valve 125 for reciprocating the same, and a pair of synchronously rotating complementary cams, each having three concentric portions of different radii and eccentric portions so related 130

to the concentric portions that the valve moves in two steps in one direction, and one step in the opposite direction, the sum of the radii of the portions of the cams engaging the said element being constant for every position of the cams.

In testimony whereof I have signed my

name to this specification in the presence of two subscribing witnesses.

JAMES KEISTER.
